[57] **CLAIM**

The ornamental design for a cable hanger, substantially as shown.

DESCRIPTION

FIG. 1 is a view in perspective of a cable hanger as seen from the top side and one end showing my new design; FIG. 2 is a view in top plan thereof to an enlarged scale; FIG. 3 is a view in bottom plan thereof to an enlarged scale;

FIG. 4 is a view in end elevation thereof as seen from the end opposite that shown in FIG. 1; and

FIG. 5 is a view in side elevation thereof as seen from the side opposite that shown in FIG. 1.
